UNITED STATES PATENT OFFICE.

ARNOLD SESSLER, OF NEW YORK, N. Y.

DESIGN FOR A STOCKING.

SPECIFICATION forming part of Design No. 28,276, dated February 8, 1898.

Application filed November 28, 1896. Serial No. 613,839. Term of patent 7 years.

To all whom it may concern:

Be it known that I, ARNOLD SESSLER, a citizen of the United States, residing at New York city, in the county and State of New York, 5 have invented and produced a new and original Design for a Stocking, of which the following is a specification.

The accompanying drawing illustrates in perspective a stocking embodying my new and original design.

The leading or material feature of my design for a stocking consists of a ridge or bead C, extending entirely around the stocking immediately below the ankle, and a flat portion upon the bottom of the foot of the stock- 15

ing, as represented in the drawing. The ridge or beading C, when the stocking is in a substantially vertical position, extends in a practically horizontal plane.

Having now described my invention, what 20 I claim as new, and desire to secure by Letters Patent, is—

The design for a stocking as herein shown and described.

This specification signed and witnessed this 25 23d day of November, 1896.

ARNOLD SESSLER.
